UNITED STATES PATENT OFFICE.

HERBERT E. VAN DORN, OF CHICAGO, ILLINOIS, ASSIGNOR TO VAN DORN GIRDER PLATE COMPANY, A CORPORATION OF ILLINOIS.

AUXILIARY FLOOR FOR RAILWAY-CARS.

1,279,183.

Specification of Letters Patent. Patented Sept. 17, 1918.

Application filed January 29, 1916. Serial No. 214,278.

To all whom it may concern:

Be it known that I, HERBERT E. VAN DORN, a citizen of the United States, residing at Chicago, county of Cook, State of Illinois, have invented a certain new and useful Improvement in Auxiliary Floors for Railway-Cars, and declare the following to be a full, clear, and exact description of the same, such as will enable others skilled in the art to which it pertains to make and use the same, reference being had to the accompanying drawings, which form a part of this specification.

My invention has for its object to produce a simple, novel and inexpensive construction and arrangement for making an auxiliary ventilated flooring a permanent part of a car while permitting it, when required, to be quickly and easily stored in a position which will leave the main car floor uncovered; whereby an auxiliary floor will always be at hand when needed and, when it is not needed, it will be stored out of the way so as to permit the car to be loaded in the usual manner of a car having no auxiliary flooring.

The various features of novelty whereby my invention is characterized will hereinafter be pointed out with particularity in the claims; but, for a full understanding of my invention and of its objects and advantages, reference may be had to the following detailed description taken in connection with the accompanying drawings, wherein:

Fig. 1 is a plan view of the auxiliary flooring for one end of a car, arranged in accordance with a preferred form of my invention, the walls of the car being indicated conventionally;

Fig. 2 is a view similar to Fig. 1, showing one element of the auxiliary floor folded back upon an adjacent section;

Fig. 3 is a section on an enlarged scale taken approximately on line 3—3 of Fig. 1;

Fig. 4 is a transverse section, on the same scale as Figs. 1 and 2, through a car, showing the floor stored in one end of the car;

Fig. 5 is a side elevation of that end of the car shown in Fig. 4, a part of the side wall being broken away in order more clearly to show the auxiliary flooring; and

Fig. 6 is a top plan view of the auxiliary flooring as it appears in Figs. 4 and 5, only a fragment of the flooring being shown, and

the adjacent side wall of the car being indicated conventionally.

In carrying out my invention I place in each end of a car an auxiliary flooring unit extending the width of the car and having a length such that when made in two halves separated from each other along a transverse line and folded so that one half lies upon the other, the folded unit may be placed upright against the corresponding end wall of the car. In order that the auxiliary flooring may be permanently attached to the car, I prefer to hinge each unit to the bottom of the car in the vicinity of one of the car ends so that the two halves of each unit, which are also hinged together, may be swung up against the end wall about the hinges which connect the unit to the car. This arrangement, because of the comparatively great length of each unit makes it difficult to fold one half upon the other and again unfold it. One of the features of my invention has to do with a simple construction and arrangement which will permit the units to be folded and unfolded easily and conveniently.

Referring to the drawings, 1 represents a loose ventilated flooring structure having a width equal to the width of a car and a length as great as possible, usually approximately half the length between one end of the car and the central doors. The member 1 is hinged to the car floor near one end of the car, preferably to the upper ends of posts, 2, secured to the car floor. That half of each auxiliary floor unit next to the central doors is made up of two sections, 3 and 4, separated from each other along a longitudinal line, preferably along the longitudinal center of the car. Each of the sections 3 and 4 is connected to the adjacent end of the section 1 by means of suitable hinges, 5.

A unit such as that described is placed in each end of the car and, where the car, as is usually the case, has a length more than four times the height of the interior thereof, the space between the two central doors may be occupied by one or more loose sections such for example, as illustrated in the application of William T. Van Dorn for auxiliary floor for railway cars, filed December 8, 1917, Serial No. 206,130.

When the auxiliary floor is in use it occupies the position shown in Fig. 1. When the auxiliary floor is not needed the sections 3

and 4 are folded back one at a time upon the section 1 and then the entire unit is swung upwardly about the hinges on posts 2 against the end wall, 6, of the car as indicated in Figs. 4 and 5. Suitable catches or locks, 7, may be provided for holding the folded unit in its upright position.

It will be seen that by making one half of each unit in two sections, it is a very simple matter for the workman to fold and unfold these two sections, whereas it would be almost impossible to fold one half of each unit back upon the other and again to unfold it, if each unit were made in two pieces only.

It is usually desirable that the extreme end portions of a ventilated flooring be inclined upwardly somewhat so as to bring the upper portions thereof above the openings into the ice chamber. Another feature of my invention has to do with a novel construction and arrangement which permits this increased height to be obtained at the ends of an auxiliary floor without leaving the ends permanently thicker so as to prevent the auxiliary floor from lying flat against a car wall when swung or folded up out of the way.

In the arrangement shown, that end of the section 1 farthest from the sections 3 and 4 is divided along a longitudinal line, preferably at the longitudinal center of the car, into two halves, 8 and 9, each hinged to that portion of the section 1 extending across the full width of the car as indicated at 10. Suitable adjustable devices, such as small blocks or shoes, 11, hinged, as indicated at 12, to the free ends of the sections 8 and 9, are provided for the purpose of permitting the free ends of the sections 8 and 9, that is the ends adjacent to the end wall of the car, to be raised when desired. This construction permits the sections 8 and 9 to be raised one at a time in order to adjust the blocks or shoes so as to permit these sections to assume inclined positions as shown in Fig. 3 or to lie with their upper surfaces in the same plane as the upper surface of the remainder of the auxiliary floor.

Where the two features of my invention are combined, it is desirable that the stringers or sills, 14, of the main part of the section 1 be continued throughout the entire length of this section so that the hinges 15 may be placed between these stringers and the supporting posts, 2. Thus the floor sections 8 and 9 are supported sections and do not serve to connect the floor unit to the car floor.

I claim:

1. A loose floor unit for railway cars comprising a section hinged to the car at one end, and a second section hinged thereto at the other end and comprising two parts lying side by side.

2. A loose floor unit for railway cars comprising a section hinged to the car at one end, and a second section hinged thereto at the other end and comprising a plurality of parts lying side by side.

3. A loose floor unit for railway cars made up of a half section, and two quarter sections arranged side by side and hinged at corresponding ends to one end of the half section.

4. A loose floor unit for railway cars made up of an end section and a plurality of sections lying side by side and hinged at corresponding ends to one end of the afore said section.

5. A loose floor unit for railway cars divided into two parts hinged together along a transverse line, one of said parts being divided into two elements along a line at right angles to the aforesaid line.

6. A loose floor unit for railway cars comprising a plurality of sections extending from one side of the car to the other and from the door to one end, said sections being hinged together to permit them to be folded up, and a hinge connection between the said unit and the car at said end of the car.

7. A loose floor for railway cars comprising a section having a width approximately equal to the width of the car and a length approximately equal to the height of the interior of the car, and a second section of approximately the same size as the aforesaid section hinged at one end to one end of the latter, said second section being divided into a plurality of parts along longitudinal lines.

8. A loose floor unit for railway cars comprising a section having a width approximately equal to the width of the interior of the car and a length approximately equal to the height of the interior of the car, said section being hinged to the car in proximity to one end of the latter, a second similar section hinged to the free end of the first section and divided into a plurality of parts along longitudinal lines.

9. A loose floor section having at one end an element of less width than the car hinged thereto at the inner end, and adjustable feet carried at the free end of said element.

10. A loose floor for railway cars comprising a plurality of sections extending from one side of the car to the other and including a plurality of sections lying side by side and hinged to the remainder to permit them to be folded up separately about transverse axes, and hinge connections between the said floor and the car at one end of the car.

11. A loose floor unit for railway cars comprising a section hinged to the car at one end, and a second section hinged thereto at the other end, said second section having a width sufficiently less than the width of

the car to permit a person to walk past the same in the car without stepping on it.

12. A loose floor unit for a railway car comprising a section hinged at one end to one end of the car, and a second section hinged to the first section at the other end of the latter, said second section being suffi-

ciently narrower than the width of the car to permit a person to walk beside the same in the car.

10 In testimony whereof, I sign this specification.

HERBERT E. VAN DORN.
